[57] CLAIM

The ornamental design for bobbin for thermal transfer film, as shown and described.

DESCRIPTION

FIG. 1 is a front elevational view of a bobbin for thermal transfer film showing my new design;

FIG. 2 is a view identical to FIG. 1 but indicating section lines thereon;

FIG. 3 is a left side view of the bobbin of the present invention;

FIG. 4 is a right side view thereof;

FIG. 5 is a sectional view taken along lines 5—5 of FIG. 2;

FIG. 6 is a sectional view taken along lines 6—6 of FIG. 2;

and,

FIG. 7 is a perspective view of the bobbin of the present invention depicted in a condition loaded with thermal transfer film in its environmental use, the broken lines showing the film being for illustrative purposes only and forming no part of the claimed design.
